UNITED STATES PATENT OFFICE.

HENRY C. BAINBRIDGE, OF BROOKLYN, NEW YORK.

ORNAMENTAL CARD.

SPECIFICATION forming part of Letters Patent No. 351,037, dated October 19, 1886.

Application filed May 1, 1886. Serial No. 200,802. (No model.)

To all whom it may concern:

Be it known that I, HENRY C. BAINBRIDGE, of Brooklyn, in the county of Kings and State of New York, have invented a new and useful 5 Improvement in Ornamental Cards, of which the following is a specification.

My invention is applicable to cards for New Year's visiting, Christmas, birthday, ménus, programmes, and other purposes; and the object of the invention is to provide a neat and attractive combination, with a card, of a band of chenille or other fabric surrounding the card.

The invention consists in an ornamental card having a notched edge and a band of fabric 15 rove through the notches around the edge of the card. This band or fabric may be an ornamental cord, a very narrow ribbon of plush or other material, or chenille, and I find it advantageous to employ a chenille band having 20 its warp formed of wires, so that it will be more readily retained in the notches of the card.

In the accompanying drawings, Figure 1 represents a face view of a card embodying my invention, the band or fabric at one corner portion being removed in order to more 25 fully show the notches in the card. Fig. 2 is an edge view of the card, and Fig. 3 represents a portion of chenille band having its warp formed of wires.

Similar letters of reference designate corresponding parts in the several figures.

A designates the card, which may be of any suitable material, and which is provided at intervals around its margin with notches b. These 35 notches, as shown in Fig. 1, will preferably be slightly undercut or dovetailed—that is to say, the opening or mouth of the notch at the extreme edge of the card will be of a width less than the diameter or width of the notch in- 40 ward of the edge.

The card notched as above described has a band or fabric, B, rove through the notches, so as to present it alternately on opposite sides or faces of the card. The band or fabric B may be of any ornamental cord or a very narrow ribbon of plush or similar fabric, or of chenille; but I find it advantageous to employ for this purpose a chenille having its warp composed of wire. In Fig. 3 I have represented on a larger scale a piece of such chenille, in which c designates the twisted wires forming the warp, and c' the filling of fibrous material, which is held in place by the warp. The warp being of wire gives the band B a certain degree of stiffness, which aids in retaining the band within the notches of the card. If other fabric than chenille—such, for example, as ribbon—were employed, the ends of the ribbon or band might be tied in a bow or otherwise connected.

It will be seen that by my invention I provide a very neat and ornamental card, in which paper and a band, cord, or fabric, usually of a contrasting color, are combined in a very tasteful manner.

What I claim as my invention, and desire to secure by Letters Patent, is—

1. The ornamental card herein described, having a notched edge and a band or fabric rove through the notches, substantially as 70 herein set forth.

2. The ornamental card herein described, having a notched edge and a band or fabric of chenille with wire warp rove through the notches, substantially as herein set forth.

HENRY C. BAINBRIDGE.
